STAND FOR JEWELRY OR THE LIKE

Noble H. Baker, 5628 Lydia, Kansas City, Mo.

Filed May 1, 1964, Ser. No. 79,776

Term of patent 14 years

(Cl. D80—9)

Fig.1.

Fig.2.

Fig.3.

Fig.4.

FIG. 1 is a front elevational view of a stand for jewelry or the like, showing my new design;

FIG. 2 is a side elevational view thereof;

FIG. 3 is a front elevational view of a modified form of the stand for jewelry or the like; and

FIG. 4 is a side elevational view of FIG. 3.

I claim:

The ornamental design for a stand for jewelry or the like, substantially as shown and described.
